UNITED STATES PATENT OFFICE.

MICHAEL F. MORRISSEY, OF MUSKEGON, MICHIGAN.

FLYING-MACHINE.

1,255,105.

Specification of Letters Patent. Patented Jan. 29, 1918.

Application filed May 15, 1917. Serial No. 168,641.

To all whom it may concern:

Be it known that I, MICHAEL F. MORRISSEY, a citizen of the United States, and a resident of Muskegon, in the county of Muskegon and State of Michigan, have invented a new and Improved Flying-Machine, of which the following is a full, clear, and exact description.

An object of my invention is to provide a flying machine utilizing feathering paddle wheel units for propelling and elevating by varying the adjustment of the paddles and in which a series of paddle wheels in each unit are so arranged that the paddles may jointly form in effect a unitary paddle extending the length of the unit, the paddles of the individual wheels of the unit being arranged to be adjusted for varying their lifting and propelling action.

A further object of my invention is to provide an effective means for optionally varying the feathering movements of the paddles and holding them in any given adjustment.

Further objects of the invention and its advantages will appear as the description proceeds.

Reference is to be had to the accompanying drawings forming a part of this specification in which similar reference characters indicate corresponding parts in all the views, it being understood that the drawings are merely illustrative of one example of the invention.

Figure 1 is a diagrammatic plan view of a flying machine constructed in accordance with my invention;

Fig. 2 is a front view thereof;

Fig. 3 is a longitudinal vertical section taken through the body of the machine and illustrating the means for adjusting the feathering means;

Fig. 4 is an enlarged transverse vertical section of one of the paddle wheel units;

Fig. 5 is a vertical section on the line 5-5, Fig. 4;

Fig. 6 is an enlarged detail view in cross section, showing the manner of feathering the paddles of each wheel;

Fig. 7 is a developed view showing a portion of the cam for giving the feathering movement to the paddles, the spokes of the paddle wheel being indicated in dotted lines.

In carrying out my invention in accordance with the illustrated example, a suit-

able body 10 is provided, and arranged at the sides thereof are paddle wheel units designated generally by the numeral 11. The machine may be equipped with any desired arrangement of horizontal rudders 12, a vertical rudder 13, and ground wheels 14.

The units 11 extend laterally and they are braced by a system of guy wires, there being front and rear guys 15 and 16 horizontally disposed, as well as intermediate horizontal crossing guys 17 between adjacent pairs of units. Said guy wires brace the machine horizontally; to brace it vertically, upper and lower transverse wires 18, 19 are employed. Transverse shafts 23 are provided on which the paddle wheels 24 of each unit are mounted to turn, said shaft being relatively fixed except as it may be turned for feathering the paddles as will appear. Adjacent to the body 10 the shafts have bearings in brackets 20 or the like, while on the outer end of each shaft is a fitting 21 which takes the outer ends of the various guy wires 15, 19, the said fittings being essentially of four-armed form in the illustrated example, said arms receiving the respective guy wires. Each fitting 21 has a thrust bearing 22 whereby the ends of the shafts 23 will take the thrust or tension of the guy wires, which are firmly tightened up, the arrangement thus relieving the paddle wheels of any end thrust due to the tautened guys.

Each paddle wheel 24 is composed of a hub 25 and spokes 26, the outer ends 26^a of which are of reduced thickness and carry the paddles 27 which are strengthened by brace wires 27^a, or the like, arranged diamond-shape on a face of the blade to prevent the same from buckling. The ends of each blade 27 are flanged at right angles at 27^b, the flanges receiving the reduced portions 26^a of the spokes and also serving to strengthen the paddle. The hubs 25 of the respective wheels 20 are halved, the halves being flanged as at 25^b, the flanges being united by bolts 25^a or the like, see Fig. 6, whereby the several wheels are connected and the inner hub 25 is integral with a sleeve or hollow shaft 28 adapted to revolve about the shafts 23. The shaft 28 is driven in any suitable manner, there being shown a sprocket wheel 29 driven by belts 29^a from any approved motor at A, Fig. 3. Roller bearings or ball bearings are provided at 30 adjacent to the ends of the shaft 23.

In order to turn the spokes 26 through the

required angle for feathering, cam collars 31 are keyed on the shaft 23 and the hubs 25 are hollow to house said collars. Each collar 31 has a peripheral cam groove 33 receiving the enlargement or head 32 on the head of a spoke 26 as shown in Figs. 4, 6 and 7. In the developed view, Fig. 7, it will be seen that the cam groove is defined at one side by a wall 34 and that the walls vary. In practice, the cam groove is so formed that the paddles for 120° will be so disposed as to present broad sides on the downward movement, the several paddles in this position, as seen at the bottom of Fig. 4, constituting in effect a single paddle extending the length of the unit. The paddles are of a width to overlap when thus disposed broadside and the action of the cam grooves 33 in alternate collars 31 are such as to turn alternate blades 20 to the right and left for feathering in the upward movement and in fact for about 240° of travel. The heads 32 on the spokes are rounded for approximately half the periphery and the remaining peripheral surface is 25 in the form of straight surfaces 35 at right angles to each other, or approximately so.

To vary the points about the shaft 23 at which the angular position of the blades will be varied, the said shaft 23 is adapted to be 30 turned through a sufficient angle for the purpose. In Fig. 3 a means is illustrated for turning the shaft 23, said means comprising a lever 36 fulcrumed as at 39 on any stand 10^a or the like on the floor of the body 35 10, and said lever has a cross arm 38 thereon which is connected by wires 40 or the like with a cross arm 41 on one shaft 23. To operate the second shaft 23, by the turning 40 of the one, wires 42 connect a second cross arm 43 on the first shaft 23 with a similar cross arm 43^a on the second shaft 23. The lever 36 is locked in a given position in the usual manner to a quadrant 37.

To give stability to each wheel 24 of the 45 unit 11 and to the unit as a whole, each spoke 26 at the juncture of the main and reduced portions is provided with an annular band or rim 44, and a second outer rim 45 extends about the outer ends of the spokes and receives the ends of the reduced portions 26^a. Furthermore, longitudinally disposed girts 46 connect the several inner rims 44 as clearly shown in Fig. 4. A system of guy wires is employed in connection with the 55 various paddle wheels, there being guy wires 47 extending from each side of the rim 45

of each wheel 24 to flanges 48 formed on the hubs 25 between the wheels. Guy wires 49 extend from the said flanges 48 to the inner rim 44 at each side and, in addition, I provide guy wires 50 extending from each rim 44 laterally on each side to the flanges of alternate wheels so that a wire from a guy wire 50 instead of going to the next adjacent flange 48 extends to the second flange, distant from the rim 44 to which said wire is secured. It will be seen that the various guy wires and the girts give rigidity to the paddle wheel unit.

In practice when the machine is in motion 70 and it is desired to cause it to rise, the lever 36 is drawn to the rearward position to feather the paddles on the front side of the wheels at 70° or thereabouts to present the paddles flatwise on the downward motion. 75 The paddles at the rear of the wheel with the upward movement thereof will be edgewise, thus without resistance. When the machine has attained the desired height, the lever may be moved forward, thereby transmitting its motion to the shafts 23, to cause the paddles to feather at 90° or thereabouts, thus giving a greater propelling motion with still sufficient lifting motion to hold the machine afloat. The paddles move on the working stroke through approximately 120° and move when presented edgewise through approximately 240° .

I wish to state in conclusion that although the illustrated example constitutes a practical embodiment of my invention, I do not limit myself strictly to the mechanical details herein illustrated, since manifestly the same can be considerably varied without departure from the spirit of the invention as 95 defined in the appended claim.

Having thus described my invention, I claim as new, and desire to secure by Letters Patent:—

In a flying machine, a transverse normally fixed shaft, a series of individual paddle wheels mounted to turn in unison on said shaft, drive means for said paddle wheels, fixtures on the ends of said shaft, co-acting feathering means on the paddle wheels 100 and on said shaft, means to turn the shaft relatively to the said fixtures and to the said paddle wheels, and guys exerting end thrust between the said fixtures and the said shaft, independently of the paddle wheels.

MICHAEL F. MORRISSEY.
